J. D. KALVERUD

STUBBLE TORCH

Filed July 14, 1924

UNITED STATES PATENT OFFICE.

JOHN DANILSON KALVERUD, OF PLAZA, NORTH DAKOTA.

STUBBLE TORCH.

Application filed July 14, 1924. Serial No. 725,974.

To all whom it may concern:

Be it known that I, JOHN D. KALVERUD, a citizen of the Dominion of Canada, residing at Plaza, in the county of Mountrail and 5 State of North Dakota, have invented a new and useful Improvement in Stubble Torches, of which the following is a specification.

This invention relates to torches for burning stubble, grass, etc.

10 The object is to provide a simple, strong and durable burner for the above stated purpose, which may be easily handled and operated to ignite the stubble or grass around a relatively large area without the necessity to stoop or bend over to reach the same, or to keep constantly on the move to reach other areas.

Another object is to provide a burner or torch of this character which may be easily 20 supported in the hands of the operator, at the end of a long handle, in proper position to bring the ignition means close to the surface of the ground, and spaced sufficiently from the tank containing the fuel oil to 25 avoid danger of explosion.

A final object is to provide a torch or burner of this class which may have one or more separate igniting members in the form of wicks capable of maintaining flames sufficiently in advance of the fuel tank as to 30 be readily and constantly observed by the operator, the said tank being formed to provide a base or rest for the device when not in use, and to prevent the same from turning over as well as to support the flame ends 35 of the wicks above the ground.

A full and complete understanding of the invention may be obtained from a consideration of the following detailed description, 40 taken in connection with the accompanying drawing forming a part of this specification; it being understood that while the drawing shows a practical form of the invention, the latter is not to be confined to 45 strict conformity with the showing thereof, but may be changed or modified, so long as such changes or modifications mark no material departure from the salient features of the invention, as specifically pointed out 50 in the appended claims.

In the drawing, in which similar reference characters designate corresponding parts throughout the several figures:

Figure 1 is a longitudinal sectional view

of the improved torch, the supporting and 55 operating handle being broken away;

Figure 2 is a perspective view of the device drawn on a smaller scale;

Figure 3 is an elevation of the front end 60 drawn on the same scale as Figure 1;

Figure 4 is a view similar to Figure 2 but showing a slight modification of the invention.

Referring to the drawing, there is shown a tank 1 formed of suitable sheet metal and 65 having a capacity for sufficient kerosene oil to burn for a considerable length of time, say one-half day, which will enable the operator to burn the grass or stubble from a relatively large area of ground without the 70 necessity for refilling the said tank. As shown in Figures 2, 3 and 4, the tank is substantially triangular in cross section, having a front wall 2, and a corresponding rear wall 3, each of which has its apex 75 rounded on a relatively large circle, the sheet metal of the body proper following such arc, as at 4, while the other angles 5 of the triangle are rounded on a smaller radius and join the inclined side walls to 80 the flat base wall 6. Any desired method of joining the walls of the tank together may be employed to secure a strong, durable and leak-proof container.

Arranged in longitudinal alignment upon 85 the apex 4 of the tank, there are secured, as by riveting, brazing or otherwise, a pair of spaced sockets 7, which may be formed of strips of sheet metal bent into substantially round form and having their terminals 90 formed into attaching flanges for the purposes, said sockets being located adjacent to the end walls respectively, as clearly shown in Figures 1 and 2 of the drawing.

The rear wall 3 is provided adjacent to 95 the apex thereof, with a filling opening 8, having an outwardly-extending, threaded flange 9 surrounding the same, the latter being adapted to receive an ordinary threaded closure cap 10 in the usual manner and 100 for the usual purpose.

The front wall 2, in the simplest form of the invention, as illustrated in Figures 1, 2 and 3, is provided with an opening 11, located in line with the center of the apex 105 and adjacent to the base 6, said opening being reinforced by a plate 12 riveted or otherwise secured to the exterior face of

the front end wall 2. The plate is also provided with an outstanding flange having a threaded bore or passageway 13 registering with the opening 11 in the end wall 2.

5 A metallic tube 14, preferably somewhat longer than the tank 1 and threaded at one end, is screwed into the aforesaid passageway 13, and extends horizontally outward in front of the tank, the same being ele-
10 vated above the base wall 6 of said tank, so that when the tank is resting upon the ground or other support, the open end of the tube 14 is held in spaced relation thereto by means of the weight of an elongated handle 15
15 having one end secured in the aforesaid sockets 7, while the other, free end rests upon the said support through gravity. The handle 15 is formed of suitable, light, strong wood and may be frictionally held in
20 the sockets, or a nail or nails may be em-
ployed to prevent the handle from becoming detached from the sockets.

Suitable wicking 16 is drawn through the tube 14 by any well-known means, the excess portion of the wicking being inserted through the opening 11 and remaining within the tank to be constantly submerged in the oil or other fuel contained therein. The outer end of the wick may be drawn out the required distance to give the desired flame in the usual manner.

The construction of all the parts as thus far described is precisely the same in Figure 4, and the same reference numerals are also employed to designate the parts, the difference in construction being, however, that in place of the single, centrally-located wick tube, there are two of such tubes having wicks therein located at opposite sides of the center of the front end wall 2, and substantially at the centers of the rounded corners at the base of the tank.

In each form of the device, the wicking fills the tubes snugly so as to convey the oil or other liquid fuel to the flame end of the said tubes and at the same time, by reason of such fit, prevent the fluid from flowing freely through and out of the open end to waste the same, or possibly cause an explosion.

50 The handle 15 may be any desired length to enable the operator to conveniently handle the device and reach out as far as possible without unduly tiring himself, and, assuming that the tank is appropriately charged and the wick set and ignited, it is only necessary to stand in one position, with the handle grasped in both hands near the free end of the same and the torch may be applied to any or all parts of a given area without bending or stooping and while standing in one position, as will be readily understood. The pressure of the oil or other fuel in the tank, being above the outlet having the wick, insures a steady pres-

sure at the flame end and causes a uniform flame, and, by suspending the tank beneath the supporting handle, it will be seen that the lowermost point of the device is the end of the tube or tubes having the flame, and since said tube or tubes are held in substantially a horizontal position, in advance of the tank, there is nothing to hinder the application of the flame to the grass or stubble, and nothing to interfere with the vision of the operator who may see just where to apply the torch in a considerable circle about himself.

From the foregoing it will be seen that a simple, cheaply-manufactured and strong and durable torch has been provided for the above stated purpose, which may be easily filled with fuel sufficient to last a relatively long time; that the device may be easily and naturally carried or supported in the proper position to apply the flame, and that the latter is constantly fed, as long as the supply of fuel lasts, by the pressure of the weight of the fuel within the tank, the flame being spaced a sufficient distance to prevent any danger from the heat thereof.

What is claimed is:—

1. A torch comprising an oil tank having a front and a rear wall and a substantially flat base, an elongated handle, means provided at the top of the tank on the outside for securing one end of the handle to the tank with the main portion of the handle projecting rearwardly from the tank, a filling opening provided at a high point of the tank and having a closure cap, a substantially straight tube secured to and extending longitudinally from the front end wall of the tank adjacent to the base of the tank and communicating with the latter, said tube being located substantially parallel to the flat base of the tank, a wick mounted in and tightly fitting said tube, the arrangement of the handle and the wick tube at opposite sides of the tank serving to balance each other when the base of the tank is resting on the ground.

2. A stubble torch, comprising an oil tank of substantially triangular cross-sectional area, said tank having a front and a rear end wall, spaced, aligned sockets mounted on the apex of the triangular tank, an elongated handle having one end fitted in the sockets and extending beyond to the rear of the tank, said rear end wall having a filling opening at a high point of the tank and provided with a closure cap, a straight tubular wick holder extending forwardly and longitudinally from the front end wall of the tank and located adjacent to the base of the triangular end wall, said tube being considerably longer than the tank and communicating therewith, and a wick mounted in and tightly fitting the tube to convey oil from the tank to the free end thereof and to pre- 130

vent leakage of the oil, the arrangement of the handle and the wick tube at opposite sides of the tank serving to balance each other when the base of the tank is resting on the ground.

3. A stubble torch comprising an oil tank of substantially triangular shape in cross section, one of the sides of the triangle forming a base, spaced straps forming sockets and secured to the apex of the triangular tank, an elongated handle having one end secured in said sockets and projecting rearwardly from the tank and constituting a handle, the rear wall of the tank having a filling opening at a high point of the tank and provided with a closure cap, spaced straight

wick tubes extending forwardly and longitudinally from the front wall of the tank, adjacent to the base thereof and communicating with said tank, and a wick in each tube and tightly fitting the same to feed oil to the outer ends of the tubes and to prevent leakage of the same, the arrangement of the handle and the wick tube at opposite sides of the tank serving to balance each other when the base of the tank is resting on the ground.

In testimony that I claim the foregoing as my own, I have hereto affixed my signature.

JOHN DANILSON KALVERUD.
